APPARATUS FOR EXTRUDING METAL

Charles James Beaver and Thomas James Fairfield, Bowdon, England, assignors to W. T. Glover and Company Limited, Manchester, England, a British company

Application June 20, 1938, Serial No. 214,796
In Great Britain June 23, 1937

6 Claims. (Cl. 207—4)

This invention relates to that type of apparatus for the extrusion of metal in which molten metal is fed into the outer part of a cylindrical container, is allowed to cool there and is then forced by a ram towards the inner end of the container, where it passes out in the plastic state by way of a die or dies. In such apparatus, after the working stroke has been completed, the ram is drawn back relative to the container or vice versa and the further charge of molten metal is fed into the space between the ram and the remaining part of the previous charge at the inner end of the container. It will be seen that the operation of this apparatus is intermittent and it has been recognised that this kind of operation has many disadvantages.

By arranging two or more containers (each with its ram) to deliver into a single space, which may be spoken of as an extrusion chamber, from which the plastic metal passes into the die and by making the working strokes of the rams at the appropriate time intervals it appears possible to produce a continuous output from the apparatus. But in order to do this it is necessary to provide some means to prevent the working stroke of one ram from forcing back metal into a container from which the ram has been withdrawn for the purpose of re-filling the container with molten metal. The metal in the delivery end of each container, and in the extrusion chamber, and the passages between this and these, is in the plastic state. Accordingly, no ordinary mechanical valve can be used to prevent the backward movement of the material.

The present invention supplies an effective means of restraining the metal in the extrusion chamber from being forced back into a container when the pressure therein is reduced so that an effective multi-container press of the type indicated can be produced in which the containers can be filled in succession in the ordinary way, since there is no back pressure exerted on the metal in the container during filling and, in fact, no pressure is exerted there except that necessary for the working stroke. In accordance with the invention the backward movement is restrained by providing a particular disposition of the passages between the containers and the common extrusion chamber, this disposition being such that the metal flows easily from each container into the extrusion chamber, but is effectively prevented from moving to any substantial extent in the opposite direction.

It has been found that, under the ordinary working conditions of pressure and temperature

and rates of movement which are used in extrusion apparatus of the kind indicated, a pronounced angle between the directions of flow of plastic metal in two passages or a passage and a chamber at the place where they join is sufficient to prevent metal of one stream from causing back flow in the other when the forward pressure therein ceases.

Accordingly, by arranging the passages leading from the delivery end of each container and into the extrusion chamber in such a way that there is a pronounced difference between the directions of flow of the plastic metal at the junction, there is no tendency for the plastic metal to be forced back into the container from which the ram is withdrawn for the purpose of re-filling the container.

An angle of 90° or less between the directions of flow of two streams of plastic metal meeting in the extrusion chamber gives satisfactory results in practice. Angles larger than 90° would in general, result in some back flow.

It is to be noted that the invention is not directly concerned with the relative positions of the two or more containers, these may have their axes parallel to each other or inclined to each other or even in line with each other. The controlling influence, in accordance with the invention is the relative disposition of the passages from the containers to the extrusion chamber. The desired result can be obtained by placing a pair of passages so that they enter the extrusion chamber in close proximity with their end portions making an appropriate angle with each other. Another arrangement which gives satisfactory results is one in which each passage enters a circular (or approximately circular) extrusion chamber tangentially and directed round the chamber in the same sense. The passages need not enter the chamber in close proximity, in this case, but may be spaced uniformly round the chamber (e.g., for two passages the entries would be diametrically opposite). The angle between the entering stream and the movement of adjacent metal round the chamber is a small one.

The invention is further described hereinafter, by way of example, with reference to the accompanying drawings, in which:

Figure 1 is a view partly in section of a two-container extrusion apparatus adapted for sheathing electric cables;

Figure 2 is a section on the line II—II in Figure 1 looking in the direction of the arrows;

Figure 3 is a diagrammatic representation of

the metal streams entering the extrusion chamber of the apparatus shown in Figures 1 and 2;

Figure 4 is a further view of the lead streams represented in Figure 3;

5 Figure 5 is a view in section of a portion of a modified form of apparatus embodying the features of the invention; and

Figure 6 is a diagrammatic representation of the metal streams entering the extrusion chamber of the apparatus shown in Figure 5, looking in the direction of the arrow VI.

The apparatus represented in Figure 1 is a double container press intended to be used for the application of a lead sheath 1 to an electric 15 cable 2. The press comprises two cylindrical containers 3 and 4 mounted on a single die-block 5, and the axes of the containers are inclined at a sharp angle to the vertical to form a press of the so-called V-type. Molten metal passes into 20 the container 3 from a reservoir 6 formed about the outer end of the container 3 and fed with molten metal by means of a supply pipe 7. When the metal within the container 3 has cooled sufficiently to become plastic a ram 8 is 25 moved into the container 3 from the outer end, thereby expelling the metal from the inner end of the container. The ram 8 is mounted at the lower end of a piston 9 operating within a hydraulic cylinder 10 mounted above and in line 30 with container 3 by means of two tie-bolts 11. The hydraulic cylinder and piston supply the necessary pressure to extrude the plastic metal from the container 3 and to withdraw the ram 8 for the purpose of recharging the container. 35 The other container 4 is charged in a similar manner by means of a reservoir 12 and a supply pipe 13, and the plastic metal is discharged similarly by means of a ram mounted on a piston 14 which operates within a hydraulic cylinder 15 40 mounted on the container 4 by means of tie-bolts 16.

Plastic metal discharged from the inner end of each container is immediately divided into two streams, the metal from the container 3 passing 45 into two passages 17 and 18, and that from the container 4 into two passages 19 and 20. The four passages 17, 18, 19 and 20 are directed to the extrusion chamber 21 which is of substantially circular form surrounding the inner die or point 22 through which the cable 2 progresses from the rear of the die block 5. The passages converge to meet, in pairs, in proximity to points which are diametrically opposed in the wall of the extrusion chamber 21. Thus the passage 17 from 50 the container 3 converges with the passage 19 from the container 4 at a single entry 23 into the extrusion chamber. Similarly the passage 18 from the container 3 converges with the passage 20 from the container 4 at a single entry 24 into the extrusion chamber, the entry 24 being diametrically opposed to the entry 23. From the 55 extrusion chamber 21 the plastic metal is extruded between the inner die 22 and an outer die in the form of a tube 1 about the cable 2.

60 The containers 3 and 4 are discharged alternately so that there is a continuous flow of plastic metal through the dies. When the discharge from one container 3 is being completed, that is, as the corresponding ram 8 is completing its 65 stroke, the discharge of the other container 4 is commenced. Whilst the latter operation is in progress the ram 8 is withdrawn from the first container 3 which is thereupon recharged with molten metal. The metal in the container 3 70 cools at such a rate that it is in a suitable con-

dition for the next extrusion operation which will be commenced as the discharge of the other container 4 is being completed.

The pairs of passages 17, 19 and 18, 20 converge at an angle which in the arrangement illustrated is about 60°. This is the angle A in Figure 3 which indicates, in conjunction with Figure 4, the relative disposition of the metal 26 within the extrusion chamber 21 and the streams of metal, 27, 28, 29 and 30 within those portions of the passages 17, 18, 19 and 20 respectively, which are adjacent the points of entry into the extrusion chamber. It is considered for the purpose of illustration that metal is being extruded from the container 3, and that the ram is being withdrawn from the other container 4 prior to recharging. The metal streams 27 and 28 are consequently flowing into the extrusion chamber in the direction indicated by the arrows in Figures 3 and 4, and the other metal streams 29 and 30 are stationary and there is no pressure in these last mentioned streams tending to move them towards the extrusion chamber or to resist any reverse movement from the extrusion chamber. Metal of the stream 28 in the passage 18 would have to alter its direction drastically by passing round a sharp edge before it could enter the passage 20 to produce a back flow of the metal 30 therein. The stream of metal 27 in the passage 17 would have to be deflected in a similar manner to affect the metal 29 in the passage 19. In these conditions no back flow of the metal streams 29 and 30 will take place, and similar conditions are maintained during discharge of metal from the container 4 and re-charge of the container 3.

Figures 5 and 6 indicate the relative disposition of the plastic metal in the extrusion chamber and in the passages from the containers in a modified form of extrusion apparatus. In this form of apparatus two containers 36 and 37 are arranged horizontally one on each side of the extrusion chamber 38, and each is adapted to be discharged by moving a ram, such as the ram 39 in the extrusion chamber 36, inwards towards the extrusion chamber 38. The containers 36 and 37 will usually be arranged with their axes extending in alignment at right angles to the line of movement of a cable through an inner die 40 located centrally within the extrusion chamber 38. The containers 36 and 37 will be discharged alternately as in the previous illustration in order to produce a continuous flow of the extruded product. In Figures 5 and 6 are shown the metal 31 within the extrusion chamber 38, the stream of metal 32 extending from the charge of metal 33 in one container 37, and the other stream of metal 34 extending from the residue 35 of the charge in the other container 36. It is assumed for the purpose of the illustration that the charge of metal 33 in one container 37 is being pressed as the stream of metal 32, in the direction of the arrow, into the extrusion chamber 38 and that the metal 31 in the chamber 38 is circulating in a manner indicated by the arrows. The other stream of metal 34 is stationary during the withdrawal of the ram 39 in the corresponding container 36 for the purpose of recharging.

As is shown in Figure 5 the two streams of metal 32 and 34 enter the body of metal 31 within the extrusion chamber 38 tangentially at points diametrically opposite to one another and in the same sense so that the circulation of the metal 31 within the extrusion chamber 38 is effected in

the same sense irrespective of whichever stream is moving into the chamber. It is clear that there is a sharp angle between the converging directions of movement of the metal 31 in the chamber 38 and of the stream entering the chamber at the junction of each stream with the chamber. Thus the metal 31 circulating in the chamber 38 would be required to change its direction by a large angle, by passing round a sharp edge, before it could produce a reverse flow of the stream 34 away from the chamber. The same conditions will exist at the junction with the other stream of metal 32 when the extrusion pressure is removed therefrom and the chamber 15 is being fed by the stream 34. In these conditions no back flow will take place.

In extrusion apparatus constructed in accordance with the invention the length of the end parts of the passages which converge upon 20 each other or enter the extrusion chamber at an angle and which are substantially straight should be substantially greater than the width of the passage, preferably of the order of three times or more. In a practical example it has been found 25 that a passage 6 inches (15 cms.) long of circular cross-section and of a uniform diameter of $\frac{1}{8}$ inch (2.2 cms.) is of satisfactory proportions. It is to be understood that the controlling influence 30 in the present case is entirely distinct from that of the tapering passage described in the specification of United States application Serial No. 172-944. The two influences can be combined by the use of tapering passages appropriately inclined 35 to each other, but a sufficient effect is obtained without such combination. A multi-container press can be produced having the feature of the invention, such press comprising a number of containers grouped around a common extrusion chamber and each connected with it by a passage 40 or passages arranged in the manner indicated. Where such a multi-container press is to be used for sheathing an electric cable, the cable can be led into and through the centre of the group of containers by way of a passage leading 45 to an inner die located in the centre of the extrusion chamber.

What we claim as our invention is:

1. In an apparatus for extruding plastic metal from a number of cylindrical containers adapted 50 to be charged with metal from their outer ends and to be discharged, after the metal has cooled to a plastic state, from their inner ends successively at time intervals into a common extrusion chamber to produce continuous extrusion 55 therefrom, the provision of a valveless passage extending from the inner end of each container to the common extrusion chamber, each passage having a cross-sectional area substantially less than that of the associated container and being 60 so disposed that there is a pronounced difference between the directions of movement of two bodies of plastic metal at their junction, thereby preventing reverse movement of metal in any of the 65 passages when pressure therein toward the extrusion chamber ceases.

2. In an apparatus for extruding plastic metal from a number of cylindrical containers adapted

to be charged with metal from their outer ends and to be discharged, after the metal has cooled to a plastic state, from their inner ends successively at time intervals into a common extrusion chamber to produce continuous extrusion therefrom, the provision of a valveless passage extending from the inner end of each container to the common extrusion chamber, each passage having a cross-sectional area substantially less than that of the associated container and being so disposed 10 that the directions of movement of two bodies of plastic metal at their junction make an angle with each other which is not greater than 90°, thereby preventing reverse movement of metal in any of the passages when pressure therein toward 15 the extrusion chamber ceases.

3. In an apparatus for extruding plastic metal from a number of cylindrical containers adapted to be charged with metal from their outer ends and to be discharged, after the metal has cooled 20 to a plastic state from their inner ends successively at time intervals into a common extrusion chamber to produce continuous extrusion therefrom, the provision of a valveless passage extending from the inner end of each container 25 to the common extrusion chamber, each passage having a cross-sectional area substantially less than that of the associated container the length of each passage being not less than three times the width thereof, and each passage being so disposed 30 that there is a pronounced difference between the directions of movement of two bodies of plastic metal at their junction, thereby preventing reverse movement of metal in any of the 35 passages when pressure therein toward the extrusion chamber ceases.

4. In an apparatus for extruding plastic metal from a number of cylindrical containers adapted to be discharged successively at time intervals into a common extrusion chamber to produce continuous extrusion therefrom, the provision of a valveless passage extending from the inner end 40 of each container to the extrusion chamber, the passages being tangentially joined with the extrusion chamber and directed in the same sense 45 about the chamber.

5. An apparatus for extruding plastic metal comprising two cylindrical containers, means co-operating with each container to discharge plastic metal therefrom into a common extrusion 50 chamber, two passages extending from each container to the extrusion chamber, each passage from one container converging with and meeting a passage from the other container at an angle of not more than about 90°. 55

6. An apparatus for extruding plastic metal comprising two cylindrical containers, means co-operating with each container to discharge plastic metal therefrom into a common circular extrusion chamber, two passages extending one from 60 each container to the extrusion chamber, the two passages being tangentially joined with the extrusion chamber at diametrically opposite points and being directed in the same sense about 65 the chamber.

CHARLES JAMES BEAVER.
THOMAS JAMES FAIRFIELD.
